(57) **CLAIM**

The ornamental design for a finger-mounted electronic device, as shown and described.

DESCRIPTION

FIG. 1 is a front view of a finger mounted electronic device showing our new design;

FIG. 2 is a rear view thereof;

FIG. 3 is a left side view thereof, the right side being a mirror image;

FIG. 4 is a top view thereof;

FIG. 5 is a bottom view thereof;

FIG. 6 is a front left perspective view thereof;

FIG. 7 is a rear left perspective view thereof;

FIG. 8 is a front left perspective view of the finger mounted electronic device worn on a finger showing our new design; and,

FIG. 9 is a left side view thereof, showing the design worn on a finger.

The broken lines show portions of the finger mounted electronic device that form no part of the claimed design. The broken lines showing a human hand are for environmental purposes only and form no part of the claimed design.

1 Claim, 8 Drawing Sheets
